UNITED STATES PATENT OFFICE.

ALPHEUS W. ALTORFER, OF ROANOKE, ILLINOIS, ASSIGNOR TO POWER WASHING MACHINE CO., OF PEORIA, ILLINOIS, A CORPORATION OF ILLINOIS.

MECHANICAL MOVEMENT AND SUPPORT FOR WASHING-MACHINE WRINGERS.

1,176,940.

Specification of Letters Patent. Patented Mar. 28, 1916.

Original application filed July 2, 1912, Serial No. 710,625. Divided and this application filed September 12, 1912. Serial No. 719,935.

To all whom it may concern:

Be it known that I, ALPHEUS W. ALTORFER, citizen of the United States, residing at Roanoke, in the county of Woodford and

5 State of Illinois, have invented certain new and useful Improvements in Mechanical Movements and Supports for Washing-Machine Wringers, of which the following is a specification.

10 My invention relates to improvements in combined power washing and wringing mechanism and has particular reference to the support and the driving means for said mechanisms.

15 The principal object of this invention is the provision of a simple, strong and attractive support for a washing machine having means thereon for operating the machine by power and also having slidably mounted 20 thereon a frame adapted to hold a wringer mechanism with power connections to drive said wringer mechanism which is movable on the support or frame to various positions relative to the washing machine.

25 This application is a division of the application for Letters Patent filed by me on July 2nd, 1912, bearing Serial Number 710,625 for improvements in combined power washing and wringing mechanism.

30 My invention further contemplates improvements in various details in structure and design.

To the accomplishment of the foregoing and such other objects as may hereinafter 35 appear my invention consists in the construction, combination and arrangement of parts hereinafter described and then sought to be defined in the appended claims, reference being had to the accompanying drawings forming a part hereof and in which is 40 illustrated a preferred embodiment of my invention, it being understood however that various changes may be made in practice within the scope of the claims without digressing from my inventive idea.

45 In the drawings: Figure 1 represents a side elevation of my invention, the washing machine being shown in dotted lines and the sliding frame being shown in two positions in dotted lines. Fig. 2 is an end view of the back end of the machine. Fig. 3 is a section taken on line 3—3 of Fig. 1, looking in the direction of the arrow. Fig. 4 is a section taken on line 4—4 of Fig. 1,

looking in the direction of the arrow. Fig. 5 is a detail view of the operating rod for the wringer clutch and its mounting. Fig. 6 is an end view of a bracket bearing for the main shaft. Fig. 7 is a side view thereof. Fig. 8 is a side view of the stud shaft and its mounting. Fig. 9 is an end view thereof. Fig. 10 is an inside elevation of the sliding support for the vertical arms and the supplemental frame. Fig. 11 is a detail view of the gear supporting bracket, 65 and Fig. 12 is a detail section showing the manner of keying the clutch member to the shaft.

In the drawings the same reference characters are used to designate like and corresponding parts.

My invention is directed particularly to an improvement in the supporting frame for the various mechanisms employed in power washers wherein a wringer is mov- 75 ably mounted on said support so as to be placed in different positions relatively to the washing machine and is directed to a simplification of the structure and operating parts of such mechanisms. To that end the 80 frame is constructed largely of angle iron, that being the simplest and strongest material available for the purpose, thus giving the machine strength and rigidity and at the same time an attractive appearance. 85

The main frame of the machine is formed of the longitudinal side members 1, which are suitably bent or shaped as at 1' to form the vertical legs 2. These members are preferably of angle iron as shown in Figs. 2 90 and 4. The horizontal flange thereof is utilized as the support for the bottom of the frame. These angle irons may be positioned so that the horizontal flange is either at the top or at the bottom thereof, the bottom 95 of the frame being secured thereto in either position. However in the form shown they are preferably positioned with the vertical flange 3 toward the outer edge, the horizontal flange 4 forming a support for the bottom 100 5 of the frame. In this construction it is to be noted that the bottom rests flush or below the upper edge of the vertical flange 3 so as not to interfere with the sliding action of the wringer supporting frame, 105 to be hereinafter described, the edges of the bottom being slightly beveled as at 5' for that purpose. This bottom is preferably

formed of wood and has the longitudinal braces 6 which engage the edge of the horizontal flange 4 of the side members of the frame. This frame is further provided with 5 the lower transverse end members 7 which are preferably of angle iron and the upper transverse members 8. These members connect and brace the legs 2 of the frame. The lower side members 9 brace the vertical legs 10 2, being connected thereto in any suitable manner, preferably resting upon the transverse end members 7 and secured to the vertical legs. Diagonal braces are provided wherever necessary being shown at 9 at 15 the end of the support which is used for the washing machine.

On one end of the main frame, preferably the washing machine end, is mounted a supporting frame for the driving connections 20 for the washer. This frame is composed of the upwardly extending members 11 and the head or top piece 12. In this form shown these members are formed and bent from an integral strip or piece of angle iron. The 25 head or top piece 12 forms the bearing support for the upper portion of the driving mechanism for the washing machine. In this structure the bearing takes the form of the pulleys 15 which are journaled on the 30 stud shafts 13 forming a part of or attached to plates or brackets 14 which are mounted on the head or top piece 12. The driving connection is flexible, being the belt 16 which traverses the pulleys 15, being driven by the 35 pulley 17 on the main shaft 18. While a belt and pulley is preferred, still other forms of driving connection such as a chain and sprocket may be utilized. The driving pulley 19 is fastened to the shaft 18 to receive 40 power from any source. This main shaft 18 is longitudinally and centrally disposed below said bottom being journaled to said frame. One end of the main shaft 18 is journaled in the bearing shown in detail in 45 Figs. 6 and 7, comprising the securing plate or portion 20, having the flange or shoulder 21 to rest on the edge of the end member 8 and having the sleeve or journal bearing 22 formed thereon. The other end of the 50 shaft 18 is supported in a simple bearing. This shaft is grooved or formed with a keyway as at 23 for a larger part of its length preferably beginning some distance from the driving end thereof. The purpose of this 55 will appear later.

A conventional form of washing machine is indicated at 24 by the dotted lines, driven by the shaft 25 and pulley 26, which pulley frictionally engages the stretch of belt between the pulleys 15 as shown, so that when the pulley 26 is in engagement with said stretch of belt the washing machine will be driven and when it is lifted therefrom, the washing machine will not be operated. The 60 form and details however of this structure 65

are not important as they are not included in this invention.

Now in devices of this character it has been found advantageous to mount a wringer on the main frame and support so 70 that it may be moved to and from juxtaposition to the washing machine. I have found that form of wringer support which is slideable to and from the washing machine to be very advantageous for this purpose 75 and in the structure disclosed in the drawing, show such a form. This movable or sliding supplemental frame 27 comprises the vertical side members or standards 28 and the horizontal top piece 29. It is on 80 this supplemental frame that the wringer mechanism is carried by preferably being clamped to said top piece, the operating shaft for said wringer being suitably journaled thereon. In this disclosure the construction is as follows. Secured to this supplemental frame is the bearing bracket 30 in which is journaled the operating shaft 31 for the wringer, shown diagrammatically in dotted lines 32, in Figs. 1 and 2. 85 On the end of this shaft 31 is mounted the driving connection, taking the form of the pulley 33 having the handle 34 for the hand operation but which is usually driven by the flexible means 35 shown as a belt, from 90 the small pulley 36, the connection for driving which will be described at length hereinafter.

The vertical side members or standards 28 of the supplemental frame 27 are mounted 100 on suitable sliding supports or runners which rest on the main frame and are constructed so that the frictional resistance is reduced to a minimum. This is for the purpose of permitting the supplemental frame 105 which supports the wringer to be readily moved on said main frame to various positions relative to said washing machine. These sliding supports or runners also carry or support the shaft from which the wringer operating shaft is driven and in addition carry the means for operating the connections whereby the wringer mechanism may be driven forward or backward or left idle 110 at the will of the operator, said parts moving with the supplemental frame so as to be convenient and accessible.

The side members 28 are secured to the sliding supports or runners 38, preferably in sockets 37 formed therein whereby they 115 are suitably braced and rigidly held. These sliding supports or runners 38 are each provided with means adapted to bear on the side members 1 of the main frame and to be readily and easily moved thereon with a 120 minimum exertion on the part of the operator. This bearing means takes the form of the longitudinal bearing flange 39, which, as shown, preferably rests upon the upper edge of the vertical portion 3 of the angle 125 130

iron side members 1. Guiding and retaining means is provided on each runner in the form of depending lips or ears 40 which slide on the outside of the side members 1. 5 On each runner is provided means to which a suitable connecting member and supporting shelf is attached. This means takes the form of the flange or shoulder 42 on the inside of said runner. The connecting member or brace and supporting shelf will be 10 described later.

The main body portion of each sliding support or runner 38 is extended downwardly and provided with the additional 15 guiding and holding flange 41 which engages and slides under the bottom of the side member 1 of the main frame. So far as described the sliding supporting members are the same. The sliding support or runner on 20 the right hand side of the machine, looking at Figs. 2 and 4, and as shown in Figs. 5 and 10 supports and carries the clutch operating rod to be described later, being provided with an aperture or bearing 43 for 25 that purpose, while the sliding supporting member on the left hand side of the machine, looking at Figs. 2 and 4, and as shown in Figs. 1 and 4 supports and carries the short counter shaft 45 being provided with 30 the depending sleeve or bearing 44 in which said shaft is journaled. This shaft 45 is the operating shaft for the wringer having secured thereto the pulley 36. It is additionally supported by means of the bearing 46 35 formed on the bracket 47 which is secured to the connecting member or brace or supporting shelf 48, the latter being positioned on the horizontal shelves or flanges 42 referred to before. This connecting member or 40 brace forms the lower member of the supplemental frame 27 as it connects the two sliding supports or runners so that they move together bracing them so as to form practically a unitary structure. This connecting member or brace forms a horizontal 45 shelf or supporting member and carries the brackets 49, which have formed on their extremal portions the bearing sleeves 50 which engage the hubs 51 of the spaced gear 50 wheels 52 the latter being loosely mounted on the main shaft 18 and provided on the other side with the clutch faces 53. Engaging these spaced gear wheels is the beveled gear wheel 54 which is mounted on the inner 55 end of the shaft 45 which drives the wringer mechanism. These brackets are preferably three in number, an additional one being provided for the shaft 45. The main shaft 18 passes through the other two brackets and 60 sleeves, which, as stated before, bear on the outside of the hubs of the spaced gear wheels 52, so that when the supplemental frame is moved along the main frame, the gears will also be moved, as will the shaft 65 45, so that the wringer mechanism may be

operated in any position. Mounted between these spaced gear wheels 52 is the sliding clutch member 55 having the two clutch faces 56 adapted to engage with the clutch faces on said gear wheels 52. This member 55 is bored to fit said main shaft 18 and is provided with a rib or projection 57 adapted to fit in said groove 23 whereby it is slidably keyed to said shaft and locked for rotation therewith always. This clutch 70 member is provided with a groove 58 for the arms 59 of the operating lever 60 which has the horizontal portion 61 journaled in a bearing 62 which is secured to the underside of the connecting brace 48, and the horizontal portion 61 of the operating lever also extending through the aperture 43 in the sliding support 38 and then being turned upwardly to extend along the vertical side member 28 of the supplemental frame, as at 75 63, and provided with the out-turned handle 64. The vertical portion 63 of this operating lever is formed at a slight inclination to the perpendicular, as shown at Fig. 4, and is normally adapted to engage the notches 65 80 in the locking member 66 secured to one of the side members 28 of the supplemental frame. It is obvious that by springing the vertical portion 63 of the operating lever out of engagement with said locking member 85 and moving it to either one of the end notches, as indicated in dotted lines in Fig. 5, that the clutch member will be thrown into engagement with one of the gear wheels 90 52, thus driving the shaft 45, pulleys 36 and 33, shaft 31, and wringer 32 in one direction, and, by moving said operating handle into engagement with the other end notch, the movement of the wringer will be reversed. Further, by leaving the handle in the central 95 notch, as indicated in Fig. 5 in full lines, the clutch member will not engage the clutch face on either gear wheel, and the wringer will not be operated. This disclosure is 100 made to show a preferred form of the operating mechanisms to operatively connect the wringer mechanism to the main shaft. It is obvious that numerous mechanical equivalents may be utilized in place of the specific structure shown. 105

It is to be noted particularly that I have provided a very simply constructed and operated mechanism. By having the sliding supports or runners 38 resting on the upper edge of the vertical flange 3 of the side members 1, there is produced a minimum amount of frictional resistance to the sliding movement of the supplemental frame supporting the wringer. This frame may be readily moved by the exercise of little 110 strength, the handle 67 being applied for that purpose. The wringer may be readily reversed or stopped and will remain in that position until the operating rod is disengaged from its lock. The washing machine 115 120 125 130

may be stopped at any time by removing the pulley 26 from engagement with the belt 12. Should the power fail, either mechanism may be operated by the hand as indicated.

It has been found advisable to allow for considerable working space and therefore for the use of additional tubs I provide an additional support 68 which is provided 10 with the holding extensions or members 69 fitting between the longitudinal brace members 6 of the bottom 4 and fitting between the transverse member 70 and the bottom 4 as shown in Fig. 1. This increases the 15 capacity of the support by providing room for additional tubs. This support may be attached to the main frame in various ways its object being to provide a convenient and simple method of increasing the floor or 20 bottom space of the frame.

What I claim is:

1. A machine support or frame, including longitudinal side members, end supporting members, a floor or bottom supported on 25 said side members, a supplemental frame including uprights or standards and a head or top piece connected thereto, supporting members or runners on which said uprights or standards are mounted, said supporting 30 members or runners resting on and being movable along said side members, a brace connecting said supporting members or runners, one of said supporting members or runners being provided with a bearing 35 adapted for one end of a transverse shaft and a bearing secured to said connecting brace for the other end of said transverse shaft.

2. A machine support or frame, including 40 longitudinal side members, end supporting members, a floor or bottom supported on said side members, a supplemental frame including uprights or standards and a head or top piece connected thereto, supporting 45 members or runners on which said uprights or standards are mounted, said supporting members or runners resting on and being movable along said side members, a brace connecting said supporting members or runners, one of said supporting members or 50 runners being provided with a bearing adapted for one end of a transverse shaft and a bearing secured to said connecting brace for the other end of said transverse 55 shaft and additional bearings secured to said connecting brace, said additional bearings being disposed in alignment to receive a longitudinal shaft.

3. In an apparatus of the character 60 described, a main frame, including longitudinal side members, end supporting members and a floor or bottom supported on said side members, a shaft arranged below the floor and extending longitudinally of said 65 main frame, an upstanding open frame

arranged on said main frame, a shaft journaled on said upstanding frame and arranged transversely of said main frame and below the floor thereof, and clutch controlled gearing to operatively connect said 70 transverse shaft to said longitudinal shaft, said longitudinal shaft adapted to be driven from a suitable source of power.

4. In an apparatus of the character described, a main frame, including longitudinal side members, end supporting members and a floor or bottom supported on said side members, a shaft arranged below the floor and extending longitudinally of said main frame, an upstanding open frame arranged 80 on said main frame, a shaft journaled on said upstanding frame and arranged transversely of said main frame and below the floor thereof, clutch controlled gearing to operatively connect said transverse shaft to said 85 longitudinal shaft, said clutch controlled gearing comprising spaced gears loosely mounted on said longitudinal shaft, an additional gear secured to said transverse shaft and in mesh with said spaced gears, a 90 clutch member slidably keyed to said longitudinal shaft and adapted to clutch either one of said spaced gears to said longitudinal shaft, and means to move said clutch member, into engagement with one of said spaced 95 gear wheels.

5. In an apparatus of the character described, a main frame, a shaft centrally journaled thereon and extending longitudinally thereof and being adapted to be driven 100 from a suitable source of power at one end, said shaft being provided with an extended groove or key-way, a supplemental frame movably mounted on said main frame and including uprights or standards and a top 105 piece connected thereto, supporting members or runners in which said uprights or standards are mounted, a brace member connecting said supporting members or runners, a transverse shaft journaled to one of said 110 runners and said brace member, and having a gear on its inner end and a driving member on its outer end, spaced gears loosely and slidably mounted on said longitudinal shaft with which said wheel is in mesh, bearings 115 or sleeves for said longitudinal shaft connected to said connecting brace, said sleeves or bearings being positioned in engagement with the outer faces of said spaced gear wheels, a clutch member slidably keyed in 120 said groove or key-way in the longitudinal shaft and adapted to clutch either one of said spaced gear wheels to said longitudinal shaft, and means for moving said clutch member into engagement with either of said 125 spacer gear wheels, said means being movable with said supplemental frame.

6. A mechanical movement for wringers comprising a suitable elongated support, a master-shaft having fixed bearings and ex- 130

- 5 tending longitudinally under said support, a traveling frame adjustable longitudinally on said support, a driving gear mounted on said shaft and movable with said frame, an idle-gear journaled on said frame and engaged by said driving gear, a transverse shaft journaled in bearings supported by said traveling frame adapted to be actuated through the medium of said idle-gear, and
- 10 rotary members and flexible driving means connected to said idle-gear.
7. A mechanical movement for wringers comprising a suitable support, a longitudinally disposed master-shaft having fixed bearings in said support, a traveling frame movable longitudinally on said support and comprising two upright standards, a cross plate connecting the upper ends thereof, runners to which said standards are secured movable on said support, a driven shaft mounted on said traveling frame, and actuating means for said driven shaft carried by said frame and deriving motion from said master-shaft.
- 25 8. A mechanical movement for wringers comprising a suitable support, a longitudinally disposed master-shaft having fixed bearings in said support, a traveling frame movable longitudinally on said support and comprising two upright standards, a cross-plate connecting the upper ends thereof, runners to which said standards are secured movable on said support, a driven shaft mounted on said traveling frame, a transmission shaft carried by said frame and arranged at an angle to said master-shaft, means transmitting the motion of said master-shaft to said transmission-shaft, and separate actuating means connecting said transmission-shaft and driven shaft.
- 35 9. A mechanical movement for wringers comprising a suitable support, a longitudinally disposed master-shaft having fixed bearings in said support, a traveling frame
- 40 movable longitudinally on said support and comprising two upright standards, a cross-plate connecting the upper ends thereof, runners to which said standards are secured movable on said support, a driven shaft mounted on said traveling frame, a transmission shaft carried by said frame and arranged at an angle to said master-shaft, gears transmitting the motion of said master-shaft to said transmission-shaft, and a flexible driving means and rotary members connecting said transmission-shaft and driven shaft.
- 45 10. A device of the kind specified comprising a suitable elongated support, parallel side members on the top thereof, a traveling-frame comprising runners movable on said side members, standards secured to and arising from said runners, a cross-plate connecting said standards, a driven-shaft journaled on said cross-plate, a master-shaft extending longitudinally under said support, and actuating means for said driven-shaft that are mounted on and movable with said traveling-frame and deriving motion from said master-shaft.
- 50 11. A device of the kind specified comprising a suitable elongated support, parallel side members on the top thereof, a traveling-frame comprising runners movable on said side members, standards secured to and arising from said runners, a cross-plate connecting said standards, a driven-shaft journaled on said cross-plate, a master-shaft, extending longitudinally under said support, and gearing for said driven-shaft that is mounted on and movable with said traveling-frame and deriving motion from said master-shaft.
- 55 In testimony whereof I affix my signature, in presence of two witnesses.
